ELECTRIC STEAMING IRON

Jacob I. Dickman, Los Angeles, Calif., assignor to
Samuel Bean, Los Angeles, Calif.

Application April 1, 1950, Serial No. 153,355

1 Claim. (Cl. 38—77)

1

This invention relates to electrically heated flatirons, and especially to such flatirons as have openings in the sole plate for the emission of steam or vapor onto the work in process.

The advantages of a steaming iron are well recognized. There is, however, a tendency for excess moisture to be discharged at the steam openings. By providing a steam chamber separated from these openings, drier steam may be obtained. Nevertheless, even then, droplets of water are occasionally discharged.

It is one of the objects of this invention to reduce the likelihood of the collection of moisture at the discharge openings.

It is another object of this invention to improve, in general, steaming electric irons.

It is still another object of this invention to provide a steaming iron in which the vapor is maintained in a dry condition, sufficient to prevent discharge of moisture.

This invention possesses many other advantages, and has other objects which may be made more clearly apparent from a consideration of one embodiment of the invention. For this purpose, there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claim.

Referring to the drawings:

Figure 1 is a perspective view of a flatiron incorporating the invention;

Fig. 2 is a longitudinal sectional view taken along the plane indicated by line 2—2 of Fig. 1;

Fig. 3 is a sectional view, taken along a plane corresponding to line 3—3 of Fig. 2;

Figs. 4 and 5 are sectional views, taken along a plane corresponding to lines 4—4 and 5—5 of Fig. 2; and

Fig. 6 is a diagrammatic exploded view showing the major elements.

The iron includes a sole plate 1 that may be in the form of a casting. Disposed above the sole plate 1 is a heater unit 2, and immediately above the heater unit 2 is a steam generating member 3. The heating unit 2 serves to heat the sole plate 1 and member 3 for the generation or heating of steam in a manner to be hereinafter described.

A shell 4 has its lower edge accommodated around a shoulder 5 formed on the upper side of the sole plate 1. To this shell 4 is attached a

2

handle 6 in any appropriate manner, as by screws 36 that engage threaded apertures 37 in member 3. The heating unit 2 is connected to a twin conductor 7. This twin conductor 7 passes through an extension 8 formed integrally with the shell 4. A thermostat adjustment means 9 is provided on the upper surface of the shell 4 for adjusting the current flowing through the heater unit 2.

Any appropriate fastening means, such as the screws 38, may be provided for holding the sole plate 1, steam generating member 3 and heater 2 together.

The steam generating unit 3 may also be made of a casting, and is provided with a generally triangular recess 10, formed by the aid of a core, and conforming to the tip of the iron. A plug 11 may be used to close the recess. Apertures or passageways 12 and 13 are drilled lengthwise of the member 3, and may be plugged, as by headless screws 14. These apertures lead into the chamber 10, and intersect the drilled openings 15 and 16 extending vertically upwardly from these passages or apertures 12 and 13.

A nipple 17 (Fig. 3) is threaded into the apertures 15, and is attached, as by the aid of nuts 18, to the shell 4. It extends through the shell 4 and serves as an inlet for steam from a boiler, or water, to the member 3.

A similar nipple 19 is provided to serve as the outlet for the steam generator 3. It communicates with passage 13 by way of the aperture 16. This nipple may be attached to the shell 4, as by the aid of the nuts 20.

A pipe connection 21 is provided from outlet nipple 19 to passageways in the sole plate 1. This pipe 21 may be threaded into the upper end of the nipple 19. It is connected, as by an elbow 22, into the passageway 23 extending longitudinally of the sole plate 1. This passageway communicates with passageways 24, 25, 26, and 27 formed in the sole plate 1. The passageways 23, 25, and 27 are substantially parallel, and are joined, in series, by the shorter passageways 24 and 26.

The last passageway 27 of the series connects to a chamber 32, formed as by a core, in the sole plate 1 and closed by a plug 33. A series of fine apertures 34 serve as steam outlets drilled in the bottom of the sole plate 1 for the discharge of steam or vapor.

The chamber 32 assumes the contour of the nose or tip of the iron.

When steam or water is fed into inlet 17, and the unit 2 is energized, steam is generated, or supplementally heated, in chamber 10, and can

progress through the passage 13, aperture 16, nipple 19, connection 21, elbow 22, passageways 23 to 27 to the chamber 32, and thence out through the perforations or apertures 34.

In the chamber 10 there are loosely accommodated a number of metallic elements 35. These elements are made of metal which is inert and non-corrosive in the presence of steam. The elements 35 may be inserted into the chamber 10 through the recess in the top of the unit 3 upon removal of the plug 11. They may be in the form of perforated discs, and of a size greater than the cross-section of the passages 12 and 13. Accordingly, the disc elements 35 are properly retained in the space 10.

The elements 35 operate to ensure the passage of relatively dry steam into the sole plate 1. The exposed surfaces of these elements serve to transmit heat to any droplets that may form in the chamber 10 and fall upon these elements. In this way, the expulsion of moisture by the energetic flow of steam through the perforations 34 is substantially prevented.

As the iron is used, the movement of the iron over the work serves to agitate the elements 35 in the chamber 10, ensuring that unevaporated water in chamber 10 will encounter these elements before they can pass into the sole plate 1 and will be evaporated.

The inventor claims:

In an electric iron: a sole plate having wall

means forming a space provided with discharge openings; a steam generator in juxtaposed relation with respect to said plate, said generator having means forming a chamber therein; said generator having means forming an aperture opening outwardly of said generator from said chamber; a removable closure for said aperture forming means; said generator also having a pair of elongate passageways, each communicating at one end respectively with said chamber, one of said passageways forming an inlet to said chamber, and the other of said passageways forming an outlet from said chamber; means connecting the other end of said other passageway with said space; electric heating means in heat-conducting relationship with said plate and said generator; and a plurality of separate freely movable metallic heat transfer elements loosely confined in said chamber; each of said elements being of a size to permit passage thereof through said aperture, but of larger size than said passageways, each of said elements having a recess for increasing the exposed area of the element.

JACOB I. DICKMAN.
